CARVING FORK

Bernard M. Miller, Sheffield, England

Application March 25, 1947, Serial No. 736,937

9 Claims. (Cl. 30—323)

1

This invention relates to carving forks, and particularly to forks having a removable guard member of the category described in my prior Patent No. 2,354,766 of August 1, 1944.

It is commonly known that carving forks provided with guards, both pivotal and fixed, have the disadvantage that food and grease tend to accumulate on the guard and adjacent portions of the fork member, and that it is generally difficult to clean these members because of obstructing elements and inaccessibility of soiled parts. To eliminate this shortcoming, I have invented a carving fork with a removable guard, in accordance with the above-mentioned patent. In this construction, a spring-loaded spindle was used to which a guard was pivotally attached, the guard being released by applying pressure to the spindle against the action of the spring. Although this device attained considerable commercial success, there was nevertheless a shortcoming in that the spindle would itself become detached and occasionally lost. Furthermore, in the assembly operation by a user, the proper position of the spindle could not always be determined, inasmuch as it was rotatable within the recess adapted to accommodate it.

It is primarily within the contemplation of my invention to provide a structure capable of overcoming the aforesaid shortcomings of a carving fork with a removable guard, and particularly the disadvantages noted with respect to my said patented structure. More specifically, it is an important object of my invention to provide a combination of fork, removable guard and retainer means which would enable the device to function more efficiently than any known device of the said category, and in which the only removable part is the guard. And in the attainment of this objective, I provide a guard retainer including a spindle which after assembly is permanently locked within the body of the fork, yet which will yieldably, releasably and pivotally engage the guard, and in which the spindle will be held against rotation.

It is another object of this invention to enable a longer spring to be employed, whereby the device can be operated more effectively and more conveniently than any similar device heretofore made. And in this aspect of my invention it is also an object to enable the guard to be yieldably and firmly maintained in both of its two extreme positions, and further to enable the guard retainer member to be yieldably and firmly maintained in its various operative positions, from the fully retracted to the maximum projected posi-

2

tion, and at all times to hold the retainer along a straight path substantially normal to the longitudinal extent of the fork member.

A further object of this invention is to provide a maximum sealing effect at the recesses containing the retainer, so as to prevent a clogging of such recesses with food or other foreign matter.

And it is within the contemplation of my invention to provide a simply fabricated and readily 10 assembled device capable of performing all the objectives hereinabove mentioned.

Other objects, features and advantages will appear from the drawings and the description hereinafter given.

15 Referring to the drawings,

Figure 1 is a front view of the fork containing my invention, a fragment of the handle being shown;

Figure 2 is a side view of Figure 1, showing in 20 full lines the operative position of the guard, and in dot-dash lines the inoperative position thereof;

Figure 3 is a somewhat enlarged elevation, partly in section, of the device of Figure 2, showing the relation of the retainer and guard member when in its operative position;

Figure 4 is a view like Figure 3 but with the guard in its inoperative position;

Figure 5 is a figure substantially like Figures 3 and 4, but with the guard member removed and 30 with the retainer in its maximum retracted position;

Figure 6 is a section of Figure 5 taken along line 6—6; and

Figure 7 is a perspective view of the retainer 35 member with the spring removed.

In the preferred embodiment of my invention illustrated, the fork member 10 contains a body portion 11 through which transversely extend the two co-axial inter-communicating recesses 12 and 40 13, the former being of greater diameter than the latter and of predetermined relative proportions, the juncture of said recesses forming an inner shoulder 14. Extending diametrically across the axis of said co-axial recesses, substantially at said 45 shoulder 14, is the locking pin 24, supported by said body member.

The guard retainer 15 consists of a spindle 16 comprising at the distal end a hooked lip 17, an enlarged cylindrical head 18 at the opposite end, 50 a cylindrical portion 19 adjacent the head, and an intermediate reduced portion 20, the upper surface 21 thereof adjacent the lip being flat. A part of the retainer is the cylindrical casing 22 open at the inner end and closed at the outer end 23. Said casing is disposed over the head end of

the spindle, it being preferred that said head 18 be slidably disposed within the casing and abutting the end wall 23 thereof. The casing is so proportioned that there is a space between the inner wall thereof and the said cylindrical portion 19 of the spindle, said space being sufficient to accommodate the helical spring 25. Said spring is illustrated as enveloping the spindle, one end being in abutment with the head 18, and the other end with the shoulder 14. In the position 10 illustrated in Figure 5, with the guard detached, the lip 17 engages the pin 24 so that the pin is disposed over the flat surface 21 and between lip 17 and cylindrical portion 19. The spring is so proportioned that in this position the retainer member 15 is in its fully retracted position, with the lip 17 disposed within the recess 13, and with the casing 15 in its most outwardly protruding position.

As will be observed from Figure 5, the pin 24 locks the retainer in place within the said recesses, so that it cannot become detached. The proportions of the parts are such that when the retainer is in its fully retracted position, the innermost portion 26 of the casing is still in engagement with the inner wall of recess 12; and while the parts are in this position, the upper and lower portions of the hooked lip are in slidably engagement with the inner wall of recess 13. It is thus evident that the retainer member 15 is supported in this extreme position by the walls of recesses 12 and 13; that is, the retainer is slidably supported at two spaced portions thereof, thereby preventing it from being axially displaced, and accordingly provided with substantial bearing surfaces. And as it will hereinafter more clearly appear, when the said retainer 15 is in any of its other operative positions, it is also supported at such spaced portions thereof by the walls of both recesses.

It will further be observed that in the various operative positions of the retainer, as shown in Figures 3, 4 and 5, the locking pin 24 is always in engagement with the flat surface 21 of the intermediate portion of the spindle. The arrangement is hence such that the spindle is held against rotation by the pin 24, thereby always assuring the proper positioning of the hooked lip 17 with respect to the pivot pin of the guard to be hereinafter described. There is therefore no need to adjustably rotate the retainer, as has been the case with the spindle arrangement described in my aforesaid patent.

The guard member 27 is substantially like that of the corresponding part of my previously patented invention, this member containing a pivot pin 28 adapted to be received and engaged by the hooked lip 17. The arrangement is such that said lip is in rotatable engagement with the pivot pin 28, permitting the guard to be rotatably actuated between its inoperative position as shown in Figure 4 and its operative positions shown in Figures 2 and 3. In both of these positions, and in all positions therebetween, the guard is yieldably maintained in place due to the action of the spring 25. It will be observed that both pins 24 and 28 are in parallel relation, so that the lip 17 is adapted to operatively engage either of these pins. It will be further observed that the retainer member is in an inwardly projected position when the guard is in its operative position (Figure 3), that it is in an intermediate position when the guard is inoperative (Figure 4) and that it is in its fully retracted position when the guard member has been detached, as

previously indicated (Figure 5). And in all of these positions, the spring 25 is under compression, thereby firmly and yieldably holding the coacting members in place.

To assemble the guard 27 upon the fork member, the retainer member 15 is pushed inwardly by the thumb, against the action of the spring, to the maximum projected position shown by dot-dash lines in Figure 3. In this position, the guard is mounted upon the retainer, the pivot pin 28 being positioned within the hooked lip 17. Thereafter, the manual pressure upon the retainer is released, whereupon the retainer is forced outwardly by the spring, thereby yieldably urging the pivot pin 28 and the guard inwardly until stopped by the body of the fork member.

In the fabrication of this device, specifically in the assembling of the retainer upon the fork member, the retainer is positioned within the recesses (unobstructed as yet by the pin 24) and mechanically held in the maximum projected position. Thereupon the pin 24 is driven into previously drilled holes. After this operation, the retainer is released, whereupon it positions itself as indicated in Figure 5.

It will be noted that the recesses 12 and 13 are effectively sealed by the retainer member and adjacent parts to prevent the infiltration of food or other foreign matter. In the condition 30 of the device shown in Figure 5, where the guard is not attached, the casing 22, slidably fitting within the recess 12, obviously seals that recess; and the lip 17 extending across the entire diameter of recess 13 serves as an effective seal for that recess. In the positions shown in Figures 3 and 4, the lip 17 together with the underlying intermediate portion 20 and the overlying wall of the guard member, constitute an effective encumbrance to the entrance of recess 13 to provide an effective and satisfactory seal.

In providing a casing 22, I have made it possible to employ a spring of greater length than could be used in my said prior patented structure inasmuch as the spring not only extends through the length of recess 12, but also enters the casing and extends through a substantial portion thereof. This increased length of spring permits a relatively long stroke of the retainer, and also results in a firm resilient holding together of the coacting members.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except in so far as such limitations are specified in the appended claims.

I claim:

1. A carving fork comprising a fork member having a body portion containing two co-axial intercommunicating recesses of different diameters extending therethrough and with their juncture forming an inner shoulder, a transverse locking pin extending diametrically through the common axis of the recesses in the region of said shoulder, a spring-loaded guard retainer extending within said recesses, and a guard containing a transverse pivot pin; said retainer comprising a spindle, a helical spring and a casing; the spindle containing a hooked lip at its distal end; an enlarged cylindrical head at the opposite end, a cylindrical portion adjacent the

head, and a reduced intermediate portion containing a flat surface adjacent the said lip, the lip being proportioned to slidably move through the smaller of said recesses; the casing being mounted over the head of the spindle and extending partly into the larger of said recesses and in slidable engagement with the interior wall thereof, the spring being mounted over the spindle with one end against the said head, the other end abutting against the said shoulder, at least a portion of the spring being contained within the casing; the said spring being proportioned to normally urge the retainer into a fully retracted position; a portion of said casing being in engagement with the inner wall of the larger of said recesses, a portion of the spindle being in engagement with the inner wall of the smaller of said recesses, and the said lip being in engagement with the said locking pin when the retainer is in said fully retracted position; the retainer being movable against the action of the spring to an inner operative position, the hooked lip of the spindle being engageable with the pivot pin of the guard at said inner operative position, both of said pins being parallel when the members are in said latter position.

2. A carving fork comprising a fork member having a recessed portion in the body thereof, a locking pin extending transversely through said recessed portion, a spring-loaded guard retainer slidably movable within the said recessed portion between a retracted and an inner operative position, said retainer containing at one end a lip, and a guard containing a transverse pivot pin thereon, the said lip being engageable with said locking pin when the retainer is in said retracted position and with said pivot pin when the retainer is in said operative position.

3. A carving fork comprising a fork member having a recessed portion in the body thereof, a locking pin extending transversely through said recessed portion, a spring-loaded guard retainer slidably movable within the said recessed portion between a retracted and an inner operative position, said retainer containing at one end a lip and adjacent thereto a portion with a flat surface, said surface being in underlying engagement with said locking pin, and a guard containing a transverse pivot pin thereon, the said lip being engageable with said locking pin when the retainer is in said retracted position and with said pivot pin when the retainer is in said operative position.

4. A carving fork according to claim 3, both of said pins being in parallel relation, whereby the lip will engage both pins in similar manner.

5. A carving fork comprising a fork member having a recessed portion in the body thereof, a locking pin extending transversely through said recessed portion, a spring-loaded guard retainer slidably movable within the said recessed portion between a retracted and an inner operative position, said retainer containing at one end a lip and at the other end a casing, the retainer spring having a portion thereof disposed within the casing, and a guard containing a transverse pivot pin thereon, the said lip being engageable with said locking pin when the retainer is in said retracted position and with said pivot pin when the retainer is in said operative position.

6. A carving fork comprising a fork member having a recessed portion in the body thereof, a locking pin extending transversely through said recessed portion, a spring-loaded guard retainer slidably movable within the said recessed por-

tion between a retracted and an inner operative position, said retainer containing at one end a lip and at the other end a casing, said casing being partially disposed and slidably movable within said recessed portion, the retainer spring having a portion thereof disposed within the casing, and a guard containing a transverse pivot pin thereon, the said lip being engageable with said locking pin when the retainer is in said retracted position and with said pivot pin when the retainer is in said operative position.

7. A carving fork comprising a fork member having a recessed portion consisting of two co-axial intercommunicating recesses of different proportions, a transverse locking pin extending through said recessed portion, a spring-loaded guard retainer extending within said recesses, and a guard containing a transverse pivot pin; said retainer comprising a spindle, a helical spring and a casing; the spindle containing a hooked lip at its distal end, an enlarged cylindrical head at the opposite end, a cylindrical portion adjacent the head, and a reduced intermediate portion containing a flat surface adjacent the said lip, the lip being proportioned to move through the smaller of said recesses; said flat surface being in underlying engagement with said locking pin; said casing being partially disposed and slidably movable within the larger of said recesses between a retracted and an inner operative position; the said lip being engageable with said locking pin when the retainer is in said retracted position and with said pivot pin when the retainer is in said operative position.

8. A carving fork comprising a fork member having a body portion containing two co-axial intercommunicating recesses of different diameters extending therethrough and with their juncture forming an inner shoulder, a transverse locking pin extending diametrically through the common axis of the recesses in the region of said shoulder, a spring-loaded guard retainer extending within said recesses, and a guard containing a transverse pivot pin; said retainer comprising a spindle, a helical spring and a casing; the spindle containing a hooked lip at its distal end, an enlarged cylindrical head at the opposite end, a cylindrical portion adjacent the head, and a reduced intermediate portion containing a flat surface adjacent the said lip, the lip being proportioned to slidably move through the smaller of said recesses; the spring being mounted over the spindle with one end against the said head, the other end abutting against the said shoulder, at least a portion of the spring being contained within the casing; said retainer being slidably movable between a retracted and an inner operative position, the said lip being engageable with said locking pin when the retainer is in said retracted position and with said pivot pin when the retainer is in said operative position.

9. A carving fork comprising a fork member having a recessed portion consisting of two co-axial intercommunicating recesses of different proportions, a transverse locking pin extending through said recessed portion, a spring-loaded guard retainer extending within said recesses, and a guard containing a transverse pivot pin; said retainer comprising a spindle, a helical spring and a casing; the spindle containing a hooked lip at its distal end proportioned to slidably move through the smaller of said recesses; the said spring being proportioned to normally urge the retainer into a fully retracted position;

a predetermined portion of said casing being in engagement with the inner wall of the larger of said recesses, a portion of the spindle being in engagement with the inner wall of the smaller of said recesses; and the said lip being in engagement with the said locking pin when the retainer is in said fully retracted position; the retainer being movable against the action of the spring to an inner operative position, the hooked lip of the spindle being engageable with the pivot 10 pin of the guard at said inner operative position.
